UNITED STATES PATENT OFFICE

GUADALUPE BUELNA, OF SANTA BARBARA, CALIFORNIA

SPRINKLER

Application filed June 12, 1928. Serial No. 284,817.

This invention relates to sprinklers and it has for its object the provision of a sprinkling device in which jets or nozzles through which the water issues may be caused to rotate at nearly imperceptible speeds during the distribution of the water over a relatively large area with high efficiency as the rotatable parts of the device are driven by the water during the sprinkling action thereof.

10 In sprinklers in which the water issuing from the nozzles produces rotation due to reaction, as ordinarily constructed and understood, the speed or rate of rotation is relatively great and is dependent upon such factors as nozzle port area, angularity of discharge, inclination of the discharging jets or streams, frictional resistance to rotation due to downward pressure or thrust upon the bearings of the rotatable parts, water pressure and the like and thorough and efficient wetting of the sprinkled surfaces and even distribution of water does not always result from their use.

It is therefore one of the principal objects 25 of the present invention to provide a sprinkler in which the speed of rotation of the arms or jetting or spraying elements is such that an even and thorough wetting of the surfaces within the wide area covered by the 30 sprinkler and the breaking up of the issuing water into very fine spray or a form approaching atomization is insured, and all without limiting the radius sweeping the affected area, with respect to the length of such 35 radius, and in which the length of such radius is even increased over the radii of prior forms of rotatable sprinklers of equal capacity.

A still further object of the invention is to 40 provide a rotatable sprinkling device of the impulse operated type in which the sprinkler arms may be caused to rotate at the proper rate of speed to cause the efficient distribution of the water regardless of the quantity 45 of water issuing therefrom or the pressure head of the same.

With the above and other objects in view, the invention consists in the novel and useful provision, formation, combination and inter- 50 relation of parts, members and features, all as

hereinafter described, shown in the drawing, and finally pointed out in claims.

In the drawing:

Fig. 1 is an elevational view.

Fig. 2 is a sectional elevational view showing my invention and

Fig. 3 is a sectional plan view taken on line 3—3 Fig. 2.

My invention consists in a generic sense of a chambered head provided with water distributing nozzles, and mounted for relative rotation on a water supplying source, and having means therein actuatable by the water entering said head for causing the rotation thereof.

In a more specific sense and referring particularly to the form of embodiment of the device shown in the drawing, the invention comprises a pipe 1 arranged preferably for connection at one end to a source 2 of water supply. The other end of said pipe 1 is provided with a central bore 3, for purposes presently appearing and with a plurality of spaced circumferentially arranged vertical passageways 4 that are arranged to be normally closed by a valve 5, fitting over and operable on an upstanding tubular reduced extension 1' of said pipe and held seated upon the top of said pipe 1 by a spring 6, the tension of which may be regulated by a nut 7 on said tubular extension 1'.

The pipe 1 is also provided with a plurality of lateral tangential ports 8, for causing a plurality of jets of water to be discharged therefrom, for purposes that will appear later.

Mounted for revolution upon said pipe 1 is a head 9 having a cylindrical portion 9' provided at the bottom thereof with an annular recess 9'' for a packing 10. The cylindrical portion 9' is diametrically slightly greater than the pipe 1 to provide a space 11 through which a portion of the water may travel to exert a pressure upon the packing 10 and thereby insure a water seal.

The cylindrical portion 9' of the head 9 is provided with a horizontal enlarged cylindrical chamber 12, and with a smaller chamber 13 surmounting said chamber 12, the smaller chamber having water distributing

nozzles 14 and 15 projecting therefrom. The head 9 is connected with the pipe 1 for rotation relatively thereto, by any desirable means, as for instance a bolt 16 arranged to extend freely through the central bore 3 of said pipe 1 and through the tubular extension 1' thereof and fastened, by threads or otherwise, to the top of the smaller chamber 13. The head 16' of said bolt 16 is arranged to bear against the inside end face of a central guide 1" provided at the end of the pipe 1 adjacent to the vertical circumferential passageways 4 therein.

The inner peripheral wall of the horizontal enlarged cylindrical chamber 12 is provided with a plurality of substantially eccentric surfaces 12' and 12" terminating in shoulders 12''' and 12''''. Within said chamber 12 is a pellet or impulse member 17 in the nature preferably of a cylindrical body, which as shown in Fig. 3, is disposed immediately in the area or path of a plurality of the tangential jets issuing from the ports 8 in said pipe 1 and discharging within said enlarged chamber 12. Under the influence of the jets issuing tangentially from the ports 8 and impinging tangentially upon the pellet or impulse member 17, the pellet is caused to travel circumferentially and axially against the inner periphery of the enlarged chamber. When during its revolutionary travel within said enlarged chamber 12, the pellet is caused to engage one of the eccentric surfaces 12' or 12" its speed of travel is increased until it strikes against the shoulders of one of the surfaces 12' and 12", as shown in Fig. 3, at which time, owing to the increased resistance offered by the shoulders 12''' and 12'''' to the movement of the pellet, the head 9 will be caused to be revolved by it until it escapes from one or the other of the shoulders under the force of the tangential jets.

Since the travel of said pellet within said chamber 12 is continuous under the pressure or influence of said jets, it will be apparent that the head 9 is thereby caused to revolve continuously intermittently as the impulse member alternately strikes first one shoulder and then the other.

The device is adapted for all water pressures, which vary considerably in different localities. At normal or low pressures the water will issue from the ports 8 and cause the pellet to travel within the enlarged chamber 12. Where, however, greater or higher pressures are encountered, the excess pressures of water above that required for a slow rotating operation of the head 9, will be relieved when such pressure unseats the valve 5 and permits the excess to be dissipated through the passageways 4 in the pipe 1 into the chamber 13 and eventually through the nozzles 14 and 15 and by which nozzles it is effectively and properly distributed over the

area to be sprinkled together with the water which reaches the nozzles through the ports 8.

What I claim, is:

1. A sprinkler comprising a head mounted for rotation and arranged for connection to a source of water supply, water distributing nozzles projecting from said head, an unattached member within and arranged for periodical impact with said head, and means for jetting the water into said head to cause said member to travel relatively thereto and periodically therewith. 75

2. A sprinkler comprising a head mounted for rotation and arranged for connection to a source of water supply, said head having a water outlet, and provided in the peripheral wall thereof with a shoulder, and an unattached water impelled member within and arranged to travel relatively to said head to engage said shoulder intermittently and thereby slowly rotate said head. 80

3. In a sprinkler, a supply pipe, a head rotatable thereon having a water outlet, means for jetting the water within said head, a member freely disposed within said head and arranged for circular travel therein under the influence of said water jets, and means on the peripheral wall of said head and disposed in the path of travel of said member to cause said head to be rotated intermittently by the periodical impact of said member with said means. 90

4. In a sprinkler, a supply pipe having tangential jetting ports, a head rotatable thereon having a water outlet, a member axially rotatable and revoluble within and independently of said head under the jets of water issuing from said ports and means on the wall of said head for periodically receiving the impact of said member thereby to cause an intermittent rotation of said head. 100

5. In a sprinkler, a supply pipe having tangential ports for jetting the water, a head rotatable thereon having a water outlet, a member axially rotatable and revoluble within and independently of said head by the jets of water issuing from said ports, means on the wall of said head for periodically receiving the impact of said member thereby to cause an intermittent rotation of said head, and means for controlling the discharge of water in excess of that required to drive said member. 115

In testimony whereof I have signed this specification.

GUADALUPE BUELNA.
